BRACKET FOR SUPPORTING A SHELF AND HANGER BAR

Robert R. Parks, 2800 Commerce St., Dallas, Tex.

Filed Dec. 31, 1962, Ser. No. 73,019

Term of patent 14 years

(Cl. D54—1)

FIG. 1

FIG. 2

FIG. 3

FIG. 1 is a left side elevational view of a bracket for supporting a shelf and hanger bar embodying my new design, the side opposite being a mirror image thereof;

FIG. 2 is a front elevational view thereof; and

FIG. 3 is a front and side perspective thereof.
The rear is substantially flat and plain.

I claim:

The ornamental design for a bracket for supporting a shelf and hanger bar, as shown and described.
